UNITED STATES PATENT OFFICE

171,456

DUPLICATING MACHINE

Lester F. Mitchell, Shaker Heights, Ohio, assignor
to Addressograph-Multigraph Corporation,
Cleveland, Ohio, a corporation of Delaware

Application June 12, 1952, Serial No. 20,154

Term of patent 14 years

(Cl. D64—11)

To all whom it may concern:

Be it known that I, Lester F. Mitchell, a citizen of the United States, residing in Shaker Heights, State of Ohio, have invented a new, original, and ornamental Design for a Duplicating Machine, of which the following is a specification, reference being had to the accompanying drawings, forming a part hereof:

Fig. 1 is a front perspective view of a duplicating machine, showing my new design;

Fig. 2 is a rear elevational view of the same; and

Fig. 3 is an elevational view of the opposite side to that shown in Fig. 1.

I claim:

The ornamental design for a duplicating machine, as shown.

LESTER F. MITCHELL.
